UNITED STATES PATENT OFFICE.

GEORGE MELLING, OF LANSING, MICHIGAN, ASSIGNOR OF ONE-HALF TO ALICE M. MELLING, OF LANSING, MICHIGAN.

FINGER-RING GUARD.

Application filed November 28, 1923. Serial No. 677,576.

To all whom it may concern:

Be it known that I, GEORGE MELLING, a citizen of the United States, residing at Lansing, county of Ingham, State of Michigan, have invented certain new and useful Improvements in Finger-Ring Guards, of which the following is a specification.

This invention relates to improvements in finger ring guards.

10 The main object of the invention is to provide an improved finger ring guard which is effective in retaining the ring upon the finger and which also serves as a protecting cover therefor.

15 Objects relating to details and economies of construction will appear from the detailed description to follow.

20 I accomplish the objects by the devices and means described in the following specification. The invention is defined and pointed out in the claims.

25 A structure embodying the features of my invention is illustrated in the accompanying drawing, forming a part of this application, in which:

Fig. I is a perspective view of a hand having one of my improved finger ring guards in operative position thereon.

30 Fig. II is a longitudinal section on line 3—3 of Fig. 1 through the improved guard in its preferred form.

Fig. III is a longitudinal section of the guard with a ring shown therein by dotted lines.

35 In the drawing similar numerals of reference refer to similar parts throughout the several views.

40 My improved guard comprises an annular body portion 1, preferably of rubber, which is adapted to yieldingly embrace a ring upon the finger, as shown in Fig. III. This body 1 terminates in annular rings or thickened rims 2 at each end, the whole being preferably formed integrally of rubber, 45 the body being thickened into the rims 2. These annular parts 2 are adapted to yield so that they may snugly embrace the finger, thus not only retaining the guard upon the

finger and thereby guarding the ring, but also to effectively exclude water and the like from contact with the ring. This is particularly desirable as many rings have been lost when removed for washing the hands and similar purposes, and also in swimming and bathing. The ring is also 55 protected when rough labor is to be performed, thus preventing loss or injury to the stone set.

My improved finger ring guard may be very economically manufactured and is very 60 convenient to use, the guards adjusting themselves to variations in sizes of fingers; that is, it is not necessary to provide the guards in a great variety of sizes, a few 65 sizes being sufficient to accommodate many sizes of fingers.

Having thus described my invention, what I claim as new and desire to secure by Letters Patent, is:

1. As an article of manufacture, a finger 70 ring guard comprising an annular resilient body portion to yieldingly embrace a ring upon a finger and terminating in a thickened integral finger embracing rim at each end.

2. As an article of manufacture, a finger 75 ring guard comprising a pair of resilient members to receive a finger and spaced to receive a ring between them, and a resilient relatively thin wall extending between and secured to said members constituting a housing for the ring embraced thereby.

3. A finger ring guard comprising an annular housing to embrace a ring upon a finger and terminating in integral rings at each 80 end to yieldingly embrace the finger at each side of the ring.

4. A finger ring guard comprising a pair of resilient annular members to embrace a finger at each side of the ring to be guarded, 90 and a yielding wall connecting said ring members and to embrace the ring.

In witness whereof, I have hereunto set my hand.

GEORGE MELLING. [L. S.]
